UNITED STATES PATENT OFFICE.

CHARLES WALTER WATKINS, OF DORRANCETON, PENNSYLVANIA.

SWITCH FOR TELEPHONE-LINES.

1,383,355.

Specification of Letters Patent.

Patented July 5, 1921.

Application filed August 21, 1920. Serial No. 405,063.

To all whom it may concern:

Be it known that I, CHARLES W. WATKINS, a citizen of the United States, residing at Dorranceton, in the county of Luzerne and 5 State of Pennsylvania, have invented certain new and useful Improvements in Switches for Telephone-Lines, of which the following is a specification, reference being had to the accompanying drawings.

10 This invention relates to improvements in switches for telephone lines.

An important object of the invention is to provide a device of this character by means of which a telephone is normally connected with a previously selected line or 15 series of lines but which may be operated by the elbow or foot of the person using the telephone to disconnect the same from such line of private conversation and which, upon 20 release, automatically returns to the normal connection.

A further object of the invention is to provide a device of this character which is extremely simple in construction and efficient 25 in operation and the parts of which may be readily interchanged or repaired.

A further object of the invention is to provide a switch connected normally with a selected line or lines and connectible with 30 other lines and which when connected with such other lines automatically resumes its normal connection upon release.

Further objects and advantages of the invention will become apparent throughout the 35 course of the following description.

In the accompanying drawings wherein for the purpose of illustration is shown a preferred embodiment of my invention and wherein like reference characters designate 40 like parts throughout:

Figure 1 is a plan view of an automatic switch constructed in accordance with my invention, the cover being sectioned for the purpose of illustration.

45 Fig. 2 is a side elevation of my automatic switch.

Fig. 3 is a transverse section taken there-through, and

50 Fig. 4 is an enlarged detail sectional view showing the mounting of the switch bar.

Fig. 5 is an enlarged sectional detail view, taken at right angles to that of Fig. 4.

Fig. 6 is a transverse sectional view taken

through the bar showing the mounting of the contacts thereon, and

Fig. 7 is a side elevation of the bar showing this mounting.

Referring now more particularly to the drawings the numeral 10 indicates the base preferably formed of insulating material 60 such as porcelain, vulcanite or the like and provided with openings 11 adapted for the reception of attaching means whereby it may be attached to the floor, stand, or desk. The base is provided upon its upper surface adjacent one end thereof with a pair of arcuate contacts 12 connected in any suitable manner with binding posts 13 which are preferably arranged upon the sides of the porcelain base. At the opposite end the base 70 is provided upon its surface with a series of arcuate contacts 14 and 15 arranged in pairs, these contacts being provided with binding posts 16 suitably arranged. To the binding post 13 may be connected a home circuit, to 75 the binding posts of the contacts 14 a main circuit and to the binding posts of the remaining pairs of contacts may be connected other telephonic circuits. As hereinbefore stated, the contacts 12, 14 and 15 are arcuate 80 and these contacts have as their center a point arranged centrally of the base 10, at which point the base is provided with a threaded opening 17 adapted to receive an externally threaded bushing 18. This bushing has bore 19 arranged centrally thereof. A pivot member 20 is provided having downwardly extending circular portion 21 which extends through the bore 19 of the bushing 18, a washer 22 being preferably disposed 90 intermediate the pivot member 20 and the upper face of the bushing 18. The lower end of the extension 21 extends below the lower end of the bushing 18 a short distance and is provided with a stop plate 23 of larger 95 diameter of the bore 19 secured to the extension by means of a screw 23^a or the like.

A tilting bar 24 is provided having a slot 25 formed therein which receives the pivot member 20 and is held in assembled relation 100 thereto by means of a pivot pin 26 extending through the member 20 and the bar 24 at the side of the slot. It will be seen that the bar is pivoted upon the member 20 for vertical oscillation and as the member 20 is capable 105 of rotation within the bushing 18 the bar 24

is therefore capable of limited universal movement. This bar is so shaped that when one end thereof is brought down to contact the base 10 the other end thereof is elevated.

5 Means for normally holding one end of the bar depressed are provided. By means of screws 27 a spring 28 has one end secured to the pivot member 20 and the other end resiliently engaging the other end of the 10 bar to force the same downwardly. This end of the bar is provided adjacent its outer end upon the upper side thereof with a counterweight 29 likewise urging this end of the bar downwardly. It will thus be seen 15 that the bar will normally oscillate horizontally in contact with the contacts 14 and 15 or with the insulated spaces 30 there-between side movement of the bar being limited by stops 31 to prevent any overrunning movement thereof.

Extending horizontally at each side of the bar 24 are wires 32, one wire being disposed at each side of the bar and each wire being connected with a slack wire 33, which 25 wires 33 are in turn connected with the terminals of a telephone. Contacts 34 are secured to the ends of the bar upon opposite sides thereof and connected with the wires 33. These contacts 34 comprise a vertical 30 portion 35 adapted to engage the side faces of the bar and provided with openings adapted for the reception of means whereby they may be secured to the bar. The lower end of the vertical portion 35 terminates 35 in horizontal portion 36 underlying the bar and terminating approximately centrally thereof, said horizontal portion having at its termination a down turned vertical portion 37 adapted to contact with its lower 40 end the contacts 12, 14, or 15, as the case may be. As the end of the bar corresponding to the contacts 14 and 15 is normally depressed by the spring 28 and counterweight 29 it will be seen that the contacts borne 45 by this end of the bar are normally engaged with the base contacts 14 or 15.

The end of the bar remote from that bearing the counterweight is reduced as at 38 and beyond such reduced portion is provided with an enlargement 39 forming an 50 operating arm or rest. This operating arm is adapted to receive a counterweight 40 thereon of sufficient size to overbalance the combined resistance of the counterweight 29 55 and spring 28. This counterweight may be either placed upon the upper surface of the enlarged portion 39 as indicated by the dotted lines or may be secured thereto in any desired manner.

60 A cover plate 41 is provided adapted to engage and reduce portion 42 of the base and entirely cover the mechanism thereof with the exception of the enlarged portion 39 of the bar 34. In order that the cover may 65 be placed in position it is provided with a ver-

tical slot 43 communicating with a horizontal slot 44. When the cover is placed in position the slot 43 permits the passage therethrough of the reduced portion 38 of the bar and the bar may be swung horizontally in the slot 70 44. Extending upwardly at spaced intervals corresponding to the spacing of the contacts 14 and 15 are vertical extensions of the slot 44 also of sufficient size to receive the reduced portion 38. It will be obvious 75 that when the reduced portion is entirely in one of the slots 45 the opposite end of the bar will be aligned with the corresponding contacts and will by virtue of the spring 28 and counterweight 29 be brought into 80 engagement therewith. When, however, the extension is arranged below one of the projections 46 formed by the vertical extension of the groove 44 the contacts of the adjacent end of the bar will be in engagement 85 with the base contacts 12. If desired, the projections 46 may be removed and the action of the bar governed entirely by the hand, foot, or elbow and by the counterweight 40.

It will be obvious that by employing my construction a single desk 'phone may be so arranged that the party in charge thereof may readily connect his 'phone with either the home circuit, the choice of branch circuits or with the main circuit. Assuming the 'phones throughout a home system to be equipped with switches of this description, it will readily be seen that the use of a central exchange may be dispensed with 90 100 and that all 'phones may be selectively engaged with either of a plurality of circuits at the will of the operator. If it is desired to continuously connect the 'phone for a given period with a given circuit if the circuit is 105 disposed at the end of the bar bearing the counterweight the bar need simply be shifted to bring the contacts thereof into engagement with the base contacts of the desired circuit. If at the opposite end of the bar 110 this connection may readily be secured by simply placing upon the enlarged portion 39 the counterweight 40. It will be understood that the 'phone may be readily connected 115 with any other system of the party line and that when the conversation is ended and the bar released it automatically returns to connect the main circuit. Many other arrangements of a similar character suggest themselves to those familiar with the art, each 120 being made possible by the presence of automatic return of the switch to connect a predetermined line in circuit with the switch circuit.

It will be obvious that my device, by reason of its simplicity, ease of its manufacture and adaptability and efficiency is particularly adapted for use and it will likewise be obvious that my device is capable 125 of some changes without departing from the 130

spirit of my invention. I accordingly do not limit myself to the specific construction except as so limited by the subjoined claims.

Having now described my invention, what I claim is:

1. In a switch of the type described an insulating base, a bar pivotally connected intermediate its ends with the base to swing in either a vertical or horizontal plane, pairs of contacts carried by said base upon opposite sides of said pivot points and pairs of contacts carried by the ends of said bar adapted to selectively engage the pairs of contacts on said base and a pair of conductors carried by said bar and connecting corresponding pairs of contacts carried thereby. 70
2. In a switch of the type described an insulating base, a bar pivotally connected intermediate its ends with the base to swing in either a vertical or horizontal plane, pairs of contacts carried by said base upon opposite sides of said pivot points and pairs of contacts carried by the ends of said bar adapted to selectively engage the pairs of contacts of said base, a pair of conductors carried by said bar and connecting corresponding pairs of contacts carried thereby, means for normally holding one end of said bar depressed and an operating handle formed upon the opposite end of the bar whereby said end may be depressed. 80
3. In a switch of the type described an insulating base, a bar pivotally connected intermediate its ends with the base to swing in either a vertical or horizontal plane, pairs of contacts carried by said base upon opposite sides of said pivot points and pairs of contacts carried by the ends of said bar adapted to selectively engage the pairs of contacts of said base, a pair of conductors carried by said bar and connecting corresponding pairs of contacts carried thereby, means for normally holding one end of said bar depressed and an operating handle formed upon the opposite end of the bar whereby said end may be depressed, said operating handle being likewise adapted for the reception of a counterweight whereby said last named end may be held depressed. 90
4. In a switch of the type described, a horizontal base portion, a bar connected intermediate its ends with said base portion for universal movement, pairs of contacts carried by said base at points on opposite sides of the point of connection of said bar, a pair of conductors extending longitudinally of said bar, pairs of contacts carried by said bar at each end thereof and electrically connected with said conductors, the contacts of said bar at either end thereof being adapted to engage the coacting contacts of the base when the corresponding end of the bar is depressed and the contacts at the opposite end of the bar freed from engagement with their corresponding base contacts, and means for normally holding one end of said bar depressed. 95
5. In a switch of the class described, a horizontal base portion, a vertically disposed member rotatably mounted in said base portion approximately centrally thereof, a bar pivotally connected to said member to oscillate in a vertical plane, one end of said bar being elevated above said base when the other end thereof is in contact therewith, a plurality of spaced pairs of contacts carried by said base and arranged upon opposite sides of the pivot point of said member, a pair of contacts carried by each end of said bar and adapted to coact with the corresponding contacts of said base and conductors connecting the corresponding contacts of the pairs carried by said bar. 100
6. In a switch of the class described, a horizontal base portion, a vertically disposed member rotatably mounted in said base portion approximately centrally thereof, a bar pivotally connected to said member to oscillate in a vertical plane, one end of said bar being elevated above said base when the other end thereof is in contact therewith, a plurality of spaced pairs of contacts carried by said base and arranged upon opposite sides of the pivot point of said member, a pair of contacts carried by each end of said bar and adapted to coact with the corresponding contacts of said base, conductors connecting the corresponding contacts of the pairs carried by said bar, a cover for said bar and base, and means for normally holding one end of said bar depressed, said cover having a slot formed therein, said bar being provided upon the normally elevated end thereof with a portion extending through the slot of said cover and adapted for engagement by the operator. 105
7. In a switch of the type described, a bar supported intermediate its ends for universal movement contacts carried by each end of the bar, contacts disposed beneath each end of the bar with which the contacts of the bar are adapted to selectively engage when the corresponding end thereof is depressed, the contacts at each end of the bar being disconnected with their coacting contacts when the contacts at the other end of the bar are connected with their coacting contacts, an operating member whereby one end of the bar may be depressed to cause the contacts thereof to engage their coacting contacts and means for automatically depressing the opposite end of the bar to bring the contacts thereof into engagement with their coacting contacts when the operating member is released. 110
- In testimony whereof I hereunto affix my signature.
- CHARLES WALTER WATKINS.
